(57) **CLAIM**

We claim the ornamental designs for a LED luminaire, as
shown and described.

DESCRIPTION

FIG. 1 is a front view showing an embodiment of our new
design for a LED luminaire, the back view being identical;

FIG. 2 is a right side view of the LED luminaire of FIG. 1,
the left side view being identical;

FIG. 3 is a top view of the LED luminaire of FIG. 1;

FIG. 4 is a bottom view of the LED luminaire of FIG. 1;
FIG. 5 is a first perspective view of the LED luminaire of
FIG. 1;

FIG. 6 is a second perspective view of the LED luminaire of
FIG. 1;

FIG. 7 is a front view showing another embodiment of our
new design for a LED luminaire, the back view being
identical;

FIG. 8 is a right side view of the LED luminaire of FIG. 7,
the left side view being identical;

FIG. 9 is a top view of the LED luminaire of FIG. 7;

FIG. 10 is a bottom view of the LED luminaire of FIG. 7;
FIG. 11 is a first perspective view of the LED luminaire of
FIG. 7;

FIG. 12 is a second perspective view of the LED luminaire
of FIG. 7;

FIG. 13 is a front view showing another embodiment of our
new design for a LED Luminaire, the back view being
identical;

FIG. 14 is a right side view of the LED luminaire of FIG. 13,
the left side view being identical;

FIG. 15 is a top view of the LED luminaire of FIG. 13

FIG. 16 is a bottom view of the LED luminaire of FIG. 13
FIG. 17 is a first perspective view of the LED luminaire of
FIG. 13

FIG. 18 is a second perspective view of the LED luminaire
of FIG. 13

FIG. 19 is a front view showing another embodiment of our
new design for a LED luminaire, the back view being
identical;

FIG. 20 is a right side view of the LED luminaire of FIG. 19,
the left side view being identical;

FIG. 21 is a top view of the LED luminaire of FIG. 19;

FIG. 22 is a bottom view of the LED luminaire of FIG. 19;
FIG. 23 is a first perspective view of the LED luminaire of
FIG. 19;

FIG. 24 is a second perspective view of the LED luminaire
of FIG. 19;

(Continued)

FIG. 25 is a front view showing another embodiment of our new design for a LED luminaire, the back view being identical;

FIG. 26 is a right side view of the LED luminaire of FIG. 25, the left side view being identical;

FIG. 27 is a top view of the LED luminaire of FIG. 25;

FIG. 28 is a bottom view of the LED luminaire of FIG. 25;

FIG. 29 is a first perspective view of the LED luminaire of FIG. 25;

FIG. 30 is a second perspective view of the LED luminaire of FIG. 25;

FIG. 31 is a front view showing another embodiment of our new design for a LED luminaire, the back view being identical;

FIG. 32 is a right side view of the LED luminaire of FIG. 31, the left side view being identical;

FIG. 33 is a top view of the LED luminaire of FIG. 31;

FIG. 34 is a bottom view of the LED luminaire of FIG. 31;

FIG. 35 is a first perspective view of the LED luminaire of FIG. 31; and,

FIG. 36 is a second perspective view of the LED luminaire of FIG. 31.

The portions shown in broken lines are not part of the claimed design but show the environment in which the design is associated.
